UNITED STATES PATENT OFFICE.

JOHN R. MITCHELL, OF EVANSTON, ILLINOIS, ASSIGNOR TO WILLIAM H. MINER, OF CHAZY, NEW YORK.

BUFFER-PLATE FOR PASSENGER-CARS.

1,311,988.

Specification of Letters Patent.

Patented Aug. 5, 1919.

Application filed November 22, 1918. Serial No. 263,670.

To all whom it may concern:

Be it known that I, JOHN R. MITCHELL, a citizen of the United States, residing at Evanston, in the county of Cook and State of Illinois, have invented a certain new and useful Improvement in Buffer-Plates for Passenger-Cars, of which the following is a full, clear, concise, and exact description, reference being had to the accompanying drawings, forming a part of this specification.

This invention relates to improvements in buffer plates for passenger cars.

In the operation of passenger cars having the customary vestibule diaphragm, diaphragm face plate and buffer plate, great difficulty has been encountered in providing a satisfactory buffer plate. As is well known, the buffer plate and diaphragm face plate of a railway passenger car are subjected to constant use and this action involves various unusual strains, particularly bending and torsion, due to the various relative positions assumed by the adjacent ends of two cars. It frequently occurs that the buffer plate is distorted and so permanently bent out of shape that the foot plate buckles and constitutes a source of danger to passengers due to the fact that the latter may easily get their feet caught beneath the buckled foot plate. In addition, the face plate being bent from a true plane, leaves a space beneath it and the buffer plate of the next adjacent car with consequent danger of passengers getting their feet caught in the open space or gap thus caused.

The object of my invention is to provide a simple and efficient form of buffer plate for passenger car equipment which will be free from all of the objections above noted and which will readily accommodate itself to all the various strains imposed upon it in service without injury or detriment to the vestibule equipment.

In the drawing forming a part of this specification, Figure 1 is an end elevational view of a passenger car showing my improvements in connection therewith. This view illustrates the buffer plate, foot plate and lower portions of the diaphragm face plate of the diaphragm frame. Fig. 2 is a hori-

zontal, sectional view, taken substantially on the line 2—2 of Fig. 1. In Fig. 2, a part of the foot plate is broken away and one of the end castings shown in section to more clearly illustrate the construction. And Figs. 3, 4 and 5 are vertical, sectional views on the lines 3—3, 4—4 and 5—5, respectively, of Fig. 1.

In said drawing, 10—10 denote longitudinal sills of the end platform of a passenger car, to the ends of which is secured an end sill casting 11 having the usual openings 12 and 13 for the side and buffer stems 14 and 15, respectively, of the usual passenger car buffer mechanism.

My improved buffer plate construction, as shown, consists broadly of two end castings 16—16, an outer spring plate 17, a series of inner spring plates 18—18 and a foot plate 19. Said end castings 16 are bolted or otherwise suitably secured to the lower ends of the side arms 20—20 of the usual inverted U-shaped diaphragm frame or face plate.

As shown, each end casting 16 is recessed as indicated at 21 to accommodate the corresponding lower end of the diaphragm face plate so as to render the latter flush with the casting, as clearly shown in Fig. 2. In addition, each end casting 16 is formed with upper and lower flanges 22 and 23 connected by a vertical web 24, the latter having a hook-shaped portion as indicated at 25, slotted as indicated at 26, to admit the end of the corresponding side stem 14. Each casting 16 is furthermore provided with a vertical flange 27 forming with the flange 24, a substantially square pocket 28 opened to the front of the casting.

The outer spring plate 17 extends from end casting to end casting and said spring plate is provided at each end thereof with an integrally formed hook, as indicated at 29, this hook being adapted to be positioned within the pocket 28, as shown in Fig. 2. In order that the outer face of the plate 17 may lie flush with the outer faces of the casting 16 and diaphragm face plate, the flanges 27 of the end castings are termnated within the outer plane of the castings a distance corresponding substantially to the thickness of the plate 17. The other spring

plates 18 are loosely received at their ends in the castings 16 in pockets 30 which are also formed by the flanges 24, 27, 22 and 23. Sufficient plates 18 are introduced to substantially take up the entire space between the outer plate 17 and the outer ends of the side stems 14 so that the latter are held in attached relation with the buffer plate when all the parts are assembled.

10 The foot plate 19 is strengthened at the central portion thereof by means of a plate 31 to which the foot plate is preferably riveted. At its ends, the foot plate 19 is perforated to receive the vertical pins 32—32 which pass through the foot plate, through perforations in the upper flanges 22 of the end castings, within the hooks 29 of the plate 17 and then through perforations in the lower flanges 23 of the end plates.

15 20 Said pins are held in position by any suitable means such as the washers 33 and cotters 34.

The parts are assembled as follows: After the end castings 16 have been secured to the diaphragm face plate, the side stems 14 are hooked in position and then the plates 18 and 17 applied in the order named. Thereupon, the foot plate is put in position and the pins 32 finally inserted so as to maintain all the elements in assembled relation.

25 30 In operation, it is evident that my improved buffer plate construction presents a flat face in the usual manner adapted for coöperation of the buffer plate of the next adjacent car. As the buffer plate is subjected to bending and torsional strains, particularly when excessive pressure is applied near one end, my improved buffer plate will readily accommodate itself inasmuch as it can flex about the center stem 15, as shown in dotted lines at 35 in Fig. 2. Upon removal of the eccentric pressure, it is evident that my flexible buffer plate structure will restore itself to normal position due to the inherent resiliency of the plates 17 and 18. Furthermore, flexing of the buffer plate proper as above described, will not cause buckling of the foot plate since the latter is, in effect, pivotally connected to the buffer plate by means of the pins 32.

35 40 With the arrangement shown and described, it is evident that I overcome all of the defects heretofore encountered in the usual buffer plates of rigid construction. It is evident that my construction can be applied to passenger car equipment now in service without modification thereof so far as the buffer mechanism proper is concerned and, of course, the improved construction may be applied to new cars as cheaply as

45 50 55 60 could the former rigid type of buffer plates.

Although I have herein shown and described what I now consider the preferred manner of carrying out my invention, the same is merely illustrative and I contem-

plate such changes and modifications that 65 come within the terms of the claims appended hereto.

I claim:

1. A buffer plate for passenger car equipment, said buffer plate having an inherently 70 resilient central portion adapting the buffer plate to flex without permanent set, about the usual central buffer stem.

2. A buffer plate structure for passenger car equipment comprising, two end castings 75 connected by a plurality of spring plates.

3. In a device of the character described, the combination with the end platform structure of a passenger car, central and side buffer stems, of a diaphragm face plate, 80 castings at the bottoms of the arms of said face plate and to which the side stems are attached, and a series of spring plates extending between said castings and against the rear face of which said central buffer 85 stem is adapted to bear.

4. As an article of manufacture, a buffer plate structure for passenger car equipment, said buffer plate structure comprising, two end elements inherently rigid and adapted 90 for coöperation with the usual side stems, and an inherently flexible plate bridging the space between said end elements and connected thereto, said flexible plate being adapted to bend around the center stem. 95

5. As an article of manufacture, buffer plate structure for railway passenger car equipment, said buffer plate structure including, two end castings adapted for pivotal connection with the usual side stems, and 100 a plurality of spring plates supported at their ends by said end castings and extending therebetween.

6. As an article of manufacture, a buffer plate structure for passenger car equipment, said buffer plate structure including, two end castings adapted to be rigidly secured to the lower ends of the arms of the diaphragm face plate and having also integral means for pivotally connecting the 110 same with the usual side buffer stems, a plurality of spring plates supported at their ends by said castings, and a foot plate pivotally connected at its ends to said end castings. 115

7. In car construction, the combination with the end platform structure of a passenger car, center and side buffer stems, of a diaphragm frame, buffer plate end castings secured to the lower ends of the arms of said 120 diaphragm frame, each of said end castings being provided with integral hook-like flanges for detachably pivotally connecting the same with one of said side stems, each casting having also pockets to accommodate 125 the ends of plate springs, a plurality of plate springs extending between said end castings and supported at their ends by said castings,

a foot plate, and means for pivotally connecting the ends of said foot plate with said end castings.

8. In a construction of the character described, the combination with a diaphragm face plate having depending side arms, of a buffer plate bridging the space between the

lower ends of said side arms, said buffer plate being inherently flexible.

In witness that I claim the foregoing I have hereunto subscribed my name this 5th day of Nov., 1918.

JOHN R. MITCHELL.
